(57) **CLAIM**

The ornamental design for a support for a power supply device, as shown.

DESCRIPTION

FIG. 1 is a perspective view of a support for a power supply device, showing my new design;

FIG. 2 is a front elevational view thereof;

FIG. 3 is a rear elevational view thereof;

FIG. 4 is a right elevational view thereof; the left elevational view is a mirror image of FIG. 4;

FIG. 5 is top plan view thereof;

FIG. 6 is a bottom plan view thereof; and,

FIG. 7 is a reduced-scale referential perspective view thereof showing a power supply device held by two supports of the present claimed design.

The broken line showing of a power supply and a second support is for illustrative purposes only and forms no part of the claimed design.
